UNITED STATES PATENT OFFICE.

THOMAS BENFIELD, OF NEWARK, NEW JERSEY.

DESIGN FOR A WATCH-CASE.

SPECIFICATION forming part of Design No. 21,485, dated April 19, 1892.

Application filed March 17, 1892. Serial No. 425,368. Term of patent 7 years.

To all whom it may concern:

Be it known that I, THOMAS BENFIELD, a subject of Her Majesty the Queen of Great Britain, residing at Newark, in the county of 5 Essex and State of New Jersey, have invented and produced a new and original Design for Watch-Cases, of which the following is a specification, reference being had to the accompanying drawings, forming part thereof.

Figure 1 is a plan view of a watch-case, showing my design. Fig. 2 is a sectional view thereof, taken on the line X X of Fig. 1.

As shown in the drawings, the leading or essential feature of my design consists of a 15 series of grooves or corrugations, straight in their length and concave in cross-section, as shown in Fig. 2, divided into quarters, the

corrugations A of one quarter meeting the corrugations B of the adjacent quarter at substantially right angles. The several portions may, it is manifest, be engraved, chased, or otherwise ornamented, as desired. It is also apparent that this design is applicable to lockets and other similar articles.

Having described my invention, what I 25 claim as new, and desire to secure by Letters Patent, is—

The design for a watch-case, as herein shown and described.

THOMAS BENFIELD.

Witnesses:

GEORGE COOK,
WILLIAM GOEBEL.
